UNITED STATES PATENT OFFICE

131,835

DESIGN FOR A SCALE HEIGHT GAUGE

Anthony Messana, Detroit, Mich., assignor of one-half to Micheal Magyari, Detroit, Mich.

Application December 16, 1941, Serial No. 104,666

Term of patent 14 years

To all whom it may concern:

Be it known that I, Anthony Messana, a citizen of the United States, residing at Detroit, in the county of Wayne and State of Michigan, have invented a new, original, and ornamental Design for a Scale Height Gauge, of which the following is a specification, reference being had to the accompanying drawing, forming a part thereof, in which:

Fig. 1 is a side elevational view of a scale height gauge showing my new design;

Fig. 2 is a front elevational view; and
Fig. 3 is a top plan view.

The stippled shading throughout the several drawing figures represents painted surfaces contrasting with the remaining bright metal surfaces.

I claim:

The ornamental design for a scale height gauge, substantially as shown and described.

ANTHONY MESSANA.
